(57) **CLAIM**

The ornamental design for a portable air cleaning humidifier, as shown and described herein.

DESCRIPTION

FIG. 1 is a perspective view of a portable air cleaning humidifier according to one embodiment of the present invention.

FIG. 2 is a front view of the portable air cleaning humidifier shown in FIG. 1.

FIG. 3 is a rear view of the portable air cleaning humidifier shown in FIG. 1.

FIG. 4 is a left-side view of the portable air cleaning humidifier shown in FIG. 1.

FIG. 5 is a right-side view of the portable air cleaning humidifier shown in FIG. 1.

FIG. 6 is a top plan view of the portable air cleaning humidifier shown in FIG. 1.

FIG. 7 is a bottom view of the portable air cleaning humidifier shown in FIG. 1.

FIG. 8 is a perspective view of the portable air cleaning humidifier shown in FIG. 1, wherein the portable air cleaning humidifier is mounted in a cup holder inside a vehicle; and,

FIG. 9 is a perspective view of the portable air cleaning humidifier shown in FIG. 1, wherein the portable air cleaning humidifier is placed on an office table.

Elements of the portable air cleaning humidifier in the attached figures are in broken lines for illustrative purposes only and form no part of the claimed design.

1 Claim, 8 Drawing Sheets
